ABSTRACT OF THE DISCLOSURE

Disclosed herein is a drilling mast mounted on a truck by means of a support base which is adapted to move longitudinally along the truck bed. The support base and thus the mast are also adapted to rotate about an axis vertically disposed with respect to the truck bed. A power source secured to the support base rotates a beveled drive gear and horizontal shaft, the latter being positioned coaxially inside a sleeve rotatably mounted on the support base. The sleeve has a yoke which supports the shaft of a driven bevel gear which meshes with the beveled drive gear. The two shafts of the bevel gears are perpendicular with respect to each other, with the shaft of the driven beveled gear extending transversely across a lower region of the mast for rotatably supporting it. The beveled drive gear with assistance from a belt drive actuates a rotary table for rotating a kelly and a drill bit. Two mutually skewed fluid cylinders have their upper ends connected with upper portions of the mast and their lower ends spaced outward and rearward from the mast and connected with the support base. The cylinders are connected with separate hydraulic circuits such that they may be moved in opposite or the same directions to enable rotation of the mast about either or both the driven beveled gear shaft and the beveled drive gear shaft.

This application is a continuation of application Ser. No. 619,671, filed Mar. 1, 1967 and now abandoned.

Background of the invention

Previously, portable drill masts have been developed which may be rotated to a lowered, travelling position or to an elevated, working position. It is advantageous that such drill mast could be skewed with respect to perpendicular to enable the drilling of slanted holes. For this reason apparatus has been developed which allows skewed position of the drill mast. It is difficult, however, to provide a drilling mast with an accompanying lightweight drive system free of complexities and maintenance problems and capable of effectively transmitting power through the drilling mast to the rotary table of the drilling mast while in all positions. My invention provides a power train-drilling mast combination which is free from complexities, having essentially fail safe reliability. In addition, I have provided drilling mast orientation means which enable convenient and reliable control over the angular disposition of the universally mounted drilling mast.

Brief description of the drawing

FIG. 1 is a fragmentary side elevational view of a portable drilling mast and related components constructed in accordance with the principles of my invention; FIG. 2 is an end view of the apparatus of FIG. 1; FIG. 3 is a fragmentary perspective view showing the lower portion of the drilling mast and portions of the power train which rotates the drill bit while enabling a wide variety of angular orientations of the drill mast; FIG. 4 is a side elevational view, partially in section, showing a portion of the power train of FIG. 3.

2

Description of the preferred embodiment

The numeral 11 designates a vertically disposed drilling mast, the function of which is to support a kelly 13 adapted to slide axially through, but be rotated by, a kelly drive or rotary table 15 supported on the lower extremity of the mast.

A power plant 17, here an internal combustion engine, is carried by a support base 19 which in this instance consists of a lower section 21 and an upper section 23 which is adapted to slide on the lower section. A hydraulic cylinder 25, centrally disposed on the support base 19, is adapted to reciprocate the upper section 23 of the support base along a substantially horizontal axis. Also, means which includes a bull gear 27 and a hydraulic motor drive pinion 29 are utilized to rotate the lower section 21 and thus upper section 23 of the support base about a substantially vertical axis.

Notice that the mast 11 is carried on the rearward end of the upper section 23 of the support base. Extending rearward from the power plant 17 is a drive shaft 31 which includes a universal joint and which drives the lower pulley 33 of a belt drive having an upper pulley 35. This belt drive preferably includes a housing 37 as shown in FIG. 3.

Extending rearward from the upper pulley 35 is a shaft 39 connected with a universal joint 41 which rotates another shaft 43 and beveled drive gear 45. The shaft 43 is supported by suitable bearings 47 for rotation relative to a sleeve 49 inserted in a mating aperture of suitable support means such as a pillow block 51 bolted to an upper section 23 of the support base as shown in FIG. 3.

The sleeve 49 is confined against longitudinal movement by a forward radial shoulder 53 formed thereon and by a rearward shoulder formed by a plate 55 secured to the sleeve by suitable means such as the fasteners 57 to enable convenient removal of the sleeve from the pillow block.

A driven bevel gear 59 is secured to a shaft 61 which in in turn is carried by the support base by means of the yoke 63 secured to the rotatable sleeve 49. The shaft 61 is transversely connected with a lower region of the drill mast perpendicularly to the shaft 43, having suitable bearing means 65. Preferably the shaft 61 may be easily removed from the drill mast by utilization of the removable plate 67 or equivalent. One end of the shaft 61 is secured to the pulley 69 of a drive means having a belt 72 and a lower pulley 73 which rotates the gears (not shown) of the rotary table 15 through which the kelly 13 axially slides.

In the above arrangement the mast 11 may rotate about the shaft 61 to which is secured the driven bevel gear 59. Also, the mast may rotate about the shaft 43 and the beveled drive gear 45 by means of its connection to the rotatable sleeve 49 through the yoke 63. Hence, the mast may be made to assume a wide variety of positions ranging from the horizontal or lowered, travelling position to the perpendicular, raised position shown in FIGS. 1 and 2 and to a variety of oblique positions.

Extending transversely across an upper region of the support base is an arm 71. The upper ends of two hydraulic cylinders 75, 77 are connected to an upper region of the mast 11, while their lower ends are spaced outward and rearward from the mast and connected to the outer extremities of the arm 71. Each of the cylinders is connected by means of a suitable hydraulic circuit (not shown) to a control element 79 or 81 which may be moved simultaneously in the same direction to raise or lower the mast 11 or which may be moved oppositely identical amounts to skew the mast with respect to vertical.

In order to stabilize the apparatus, especially when the mast is obliquely oriented, a plurality of outriggers 3 driven by hydraulic cylinders 85 are provided as shown in FIGS. 1 and 2.

In operation, the apparatus is transported to a selected drilling location with the mast in a lowered, travelling position (not shown) wherein its upper region lies longitudinally and essentially parallel with the truck bed. The mast is raised by moving the control elements or handles 9, 81 equal amounts in the same direction to open a valve (not shown) causing a pressure increase in the hydraulic cylinders 75, 77. The increased pressure in the cylinders moves the pistons outward, forcing the mast toward its raised position. Ultimately, the mast will assume the vertical position shown in FIGS. 1 and 2. Continued extension of the cylinders may be utilized until the mast 11 assumes an obtuse angle relative to its lowered, travelling position.

Another one of the control elements is moved to extend the hydraulic cylinder 25 an amount to achieve a selected linear relationship between the upper and lower sections 21, 23 of the support base 19. In addition, another control element may be moved to activate the hydraulic motor driven pinion 29 to rotate the support base 19 and the drilling mast 11 about a vertical axis.

When the kelly 13 and drill bit (not shown) attached to its lower end are located precisely above the selected spot on the terrain, another control element is moved to urge the kelly and drill bit downward into the earth's formations, while simultaneously the rotary table or kelly drive 15 is actuated to rotate the kelly and drill bit. When the desired depth is reached, the kelly and drill bit are retracted and the mast 11 may be rotated once again to its lowered, travelling position by moving the control elements 79, 81 in an opposite direction from that utilized to raise the drilling mast.

The drilling mast may be utilized for forming slanted holes by orienting it obliquely as seen in FIG. 1, as previously described and as viewed in FIG. 2. After cylinder 75 is extended and simultaneously the cylinder 77 retracted similar amounts, the mast 11 will be rotated counterclockwise as viewed in FIG. 2. Conversely, if the cylinder 77 is extended and the cylinder 75 retracted identical amounts, the drilling mast will be rotated clockwise as viewed in FIG. 2.

The above described universal movements of the drilling mast 11 are achieved by the use of the hydraulic cylinders 75, 77 in combination with the power train and drilling mast mounting means previously described. The mast may be raised or lowered by rotation about the shaft 61 to which is secured the driven bevel gear 9. At the same time the mast may be rotated about the shaft 43 and bevel drive gear 45, since it is connected with the sleeve 49 by means of the yoke 63. Hence, I have provided means for raising and lowering the mast and for enabling skewed dispositions thereof with respect to vertical as seen from any perspective. Such means utilizes a lightweight power train or drive system free of complexities and maintenance problems and capable of effectively transmitting power through the drilling mast to the rotary table with the mast in any position. The only components of the power train which move with the drilling mast are the rotary table, the second belt drive and the sleeve. All other power train components remain stationary with respect to the support base. Consequently, I have provided drilling mast orientation means which enable convenient and reliable control over the angular disposition over a universally mounted drilling mast.

While I have shown my invention in only one of its forms it should be apparent to those skilled in the art that it is not so limited but is susceptible to various changes and modifications without departing from the spirit thereof.

I claim:

1. A drill rig and universally mounted drilling mast comprising:

a support base;
means engaging said base for rotation of a section thereof about a substantially vertical axis;
means engaging said base for reciprocation of said section thereof along a substantially horizontal axis;
a mast carried by said support base;
a rotary table carried by said support base for rotating a kelly and drill bit;
a driven gear and shaft carried by said support base and secured horizontally to a bottom region of said mast, which is adapted to rotate relative to said shaft and gear between elevated, working positions and a lowered, non-working position;
a drive gear and shaft carried by said support base to transversely engage said driven gear;
a rotatable sleeve carried by said support base concentrically relative to said drive gear and shaft;
power means supported by said base and communicating with said drive gear and shaft;
drive means connecting said driven gear and shaft with said rotary table;
two fluid powered cylinders having their upper ends connected with said mast and their lower ends spaced outwardly and rearwardly from said mast and connected with said support base; and
control means connected separately with each of said cylinders to enable rotation of said mast about said driven gear shaft and said drive gear shaft.

2. A drill rig and universally mounted drilling mast comprising:

a support base;
a mast carried by said support base;
a rotary table carried by said support base for rotating a kelly and drill bit;
a driven gear and shaft carried by said support base and secured horizontally to a bottom region of said mast, which is adapted to rotate relative to said shaft and gear between elevated, working positions and a lowered, non-working position;
a drive gear and shaft carried by said support base to transversely engage said driven gear;
a rotatable sleeve carried by said support base concentrically relative to said drive gear and shaft;
power means supported by said base and communicating with said drive gear and shaft;
drive means connecting said driven gear and shaft with said rotary table;
two fluid powered cylinders having their upper ends connected with said mast and their lower ends spaced outwardly and rearwardly from said mast and connected with said support base; and
control means connected separately with each of said cylinders to enable rotation of said mast about said driven gear shaft and said drive gear shaft.

3. A drill rig and universally mounted drilling mast comprising:

a support base;
a mast carried by said support base;
a rotary table carried by said support base rotating a kelly and drill bit;
a driven gear and shaft carried by said support base and secured horizontally to a bottom region of said mast, which is adapted to rotate freely relative to said shaft and gear and about the same axis between elevated, working positions and a lowered, non-working position;
a drive gear and shaft carried by said support base to transversely engage said driven gear;
a rotatable sleeve carried by said support base concentrically relative to said drive gear and shaft;

power means supported by said base and communicating with said drive gear and shaft;
 drive means connecting said driven gear and shaft with said rotary table;
 remotely operable powered control means connected with said mast and connected with remote control elements spaced therefrom to enable remotely controllable powered rotation of said mast about said driven gear shaft and said drive gear shaft.
 4. The rig and universally mounted drilling mast of claim 3 wherein said remotely operable powered control means are connected to hydraulic lines for being powered by a high pressure hydraulic fluid.

[57] **ABSTRACT**

Disclosed herein is a drilling mast mounted on a truck by means of a support base which is adapted to move longitudinally along the truck bed. The support base and thus the mast are also adapted to rotate about an axis vertically disposed with respect to the truck bed. A power source secured to the support base rotates a beveled drive gear and horizontal shaft, the latter being positioned coaxially inside a sleeve rotatably mounted on the support base. The sleeve has a yoke which supports the shaft of a driven bevel gear which meshes with the beveled drive gear. The two shafts of the bevel gears are perpendicular with respect to each other, with the shaft of the driven bevel gear extending transversely across a lower region of the mast for rotatably supporting it. The beveled drive gear with assistance from a belt drive actuates a rotary table for rotating a kelly and a drill bit. Two mutually skewed fluid cylinders have their upper ends connected with upper portions of the mast and their lower ends spaced outward and rearward from the mast and connected with the support base. The cylinders are connected with separate hydraulic circuits such that they may be moved in opposite or the same directions to enable rotation of the mast about either or both the driven bevel gear shaft and the beveled drive gear shaft.
